Attorney, Agent, or Firm—King & Schickli[57] **CLAIM**

The ornamental design for a stackable/nestable bed, as shown and described.

DESCRIPTION

FIG. 1 is a perspective view of the stackable/nestable bed showing my new design;

FIG. 2 is a top plan view thereof;

FIG. 3 is a bottom plan view thereof;

FIG. 4 is a left side elevational view, the right side elevational view being a mirror image thereof; and,

FIG. 5 is a front end elevational view, the rear end elevational view being a mirror image thereof.
